UNITED STATES PATENT OFFICE.

EDWARD T. LIESS, OF HUNTINGTON, NEW YORK.

VALVE-EXTRACTOR.

Specification of Letters Patent. Patented Aug. 17, 1920.

1,350,163.

Application filed October 29, 1919. Serial No. 334,245.

To all whom it may concern:

Be it known that I, EDWARD T. LIESS, a citizen of the United States, and a resident of Huntington, county of Suffolk, and State 5 of New York, have invented a new and Improved Valve-Extractor, of which the following is a full, clear, and exact description.

This invention relates to valve mechanisms and has reference more particularly to a device adapted for the extraction of valves 10 from an internal combustion engine.

An object of this invention is to provide a device for removing the valves from an internal combustion engine which can be 15 cheaply constructed and will be easy to apply.

Reference is had to the accompanying drawing forming part of this specification, in which it is understood that the drawing 20 is merely illustrative of one example of the invention, and in which—

Figure 1 is an elevation of an internal combustion engine with a part broken away to show the improved valve extractor in 25 operative position.

Fig. 2 is a side elevation of the valve extractor.

Fig. 3 is a section through Fig. 2 on the line 3—3.

Fig. 4 is a top view of the device.

Referring to the accompanying drawings by numerals, 10 indicates an internal combustion engine shown as an automobile engine having a plurality of valves 11, whose valve stems 12 are seated in bearings 13 and are reciprocated vertically by means of valve tappets 14, which reciprocate vertically in bearings 15. The valve tappets 14 may be adjusted as to length by means of bolts 16 screwed in the ends. The heads 17 of said bolts form seats for the valve stems 12. The tappets 14 and the valve stems 12 are reciprocated vertically by means of cams 18 fixed to a cam-shaft 19, said cam-shaft being connected by some means not shown to a source of power. In order to make sure that the valve properly seats when the cam 18 lowers the tappet 14, a spring 20 is provided which in ordinary engines is mounted on the valve stem 12 and is seated at one end on the frame of the engine 10, and at the other end on a cup-shaped washer 21, said washer being prevented from moving axially along the valve 50 stem under the action of the spring by

means of a pin 22 which passes laterally through the valve stem.

In order to allow the easy removal of the valve 11, I provide a collar 23 having a depending annular flange 24, said collar 60 being mounted on the bearing 13 between the end of the spring 20 and the frame of the engine 10. At each side of the collar 23 is formed a hinge 25 to which is pivoted by means of a hinge pin 26, an arm 27 having a laterally extending finger 28 at its lower end. These arms 27 are curved in cross section as shown in Fig. 3, and are of such length that when the cam 18 is raised to its highest point, the fingers 28 70 will just slip under and grip the washer 21 so that as the cam 18 is rotated to some lower position, the pin 22 will be freed from the tension of the spring and can be easily extracted, thus allowing the valve 75 11 and the valve stem 12 to be removed or to be rotated when it is desired to grind in or clean a valve. When the valve stem 12 is removed the spring, washer, and extractor cling together and can be handled 80 as a unit and removed from the engine if so desired. The hinges 25 form a very close fit around the hinge pin 26, so that when the arms are placed in any one position, they will remain in that position regardless of jars or knocks occurring in the engine.

Thus when the two arms are spread apart as shown in the right hand valve of Fig. 1, the washer 21 and the valve stem 12 are 90 free to reciprocate vertically, as the engine operates without engaging the fingers 28. The valve on the left in Fig. 1 shows the arms 27 pressed together manually to grip the washer 21. The collars are adapted to 95 remain on the engine constantly while it is in operation, and the collars may be turned so the arms of the different collars stand at different relative positions, so that said arms will not interfere with each other. 100

The device may be made of any suitable material, but I prefer to use a high grade steel which may be made very light and strong.

I would state in conclusion, while the 105 illustrated example constitutes a practical embodiment of my invention, I do not limit myself strictly to the mechanical details herein illustrated, since manifestly the same can be considerably varied without depar- 110

ture from the spirit of the invention as defined in the appended claim.

Having thus described my invention, I claim as new and desire to secure by Letters 5 Patent:-

In a valve extractor, a rigid collar adapted to be permanently positioned around a valve stem between a valve spring

and its seat, a plurality of arms hinged at one end around the periphery of said collar, and a transverse finger formed on the end of each arm opposite the hinge adapted to engage the spring washer and hold the spring in compression after the compressive force is removed.

EDWARD T. LIESS.
